B. KUGLER

LOCKED ANCHORAGE FOR WINDOW CLEANERS' HARNESS

Filed Feb. 19, 1923

Inventor
Benjamin Kugler,
By *Henry J. Gauthier*
Attorney

UNITED STATES PATENT OFFICE.

BENJAMIN KUGLER, OF CHICAGO, ILLINOIS.

LOCKED ANCHORAGE FOR WINDOW-CLEANERS' HARNESS.

Application filed February 19, 1923. Serial No. 619,978.

To all whom it may concern:

Be it known that I, BENJAMIN KUGLER, a citizen of the United States, residing at Chicago, in the county of Cook and State of Illinois, have invented new and useful Improvements in Locked Anchorage for Window-Cleaners' Harness, of which the following is a specification.

My invention relates, in its broad aspect, to a fixed and positively locked anchorage for window cleaners' harness, which is particularly adapted for use with a wooden base. More particularly my anchorage is designed to provide a positive means for engaging into the material of a base whereby to prevent disengagement of the anchorage therefrom due to over-loading or weakening of the material of such base.

In attaining the objects of my invention I employ a plurality of inherently resilient members forming tangs, which are swingable, and adapted to normally extend without the surface of the shank of an anchorage, but compressible within suitable recesses provided for that purpose in the shank. In practice it has been found that certain materials, and particularly wood, do not afford sufficient resistance to stress and strain, and weathering, to insure a permanent and safe attaching base for an anchorage for window cleaners' harness. For the purpose of surmounting this difficulty, I have devised the hereinbefore defined anchorage, the tangs of which are adapted to embed themselves in the material of the base, and exert a relatively greater resistance to withdrawal as the stress upon the anchorage is increased, or as the material of the base becomes weakened through age, weathering, or the like.

The structural elements employed to accomplish the above and other results and objects will be hereinafter more fully described in detail and specifically pointed out in the claims appended hereunto and forming a part of this specification, but the scope of the invention may only be determined by the limits defined in the claims.

In the accompanying drawings, wherein is illustrated the preferred embodiment of my invention;

Figure 1, is a side view of the principal embodiment of my invention,

Figure 2, is a front view thereof,

Figure 3, is a sectional view of the shank 55 of the anchorage.

Like characters of reference refer to like or similar parts throughout the several views of the drawings, in which:—

The numeral (1) designates the head of my anchorage, which in the present instance is elongated and has a drilled opening (2) formed adjacent to one of its ends for the purpose of receiving a screw or the like (not shown) to prevent possible turning action of the head under the stress exerted by a window cleaner's harness. Integrally formed upon the head (1) are a pair of spaced studs (3). The studs are reduced intermediate their lengths for the purpose of receiving a window cleaner's harness coupling of the type described in my patent Number 1,442,159, issued January 16th 1923, and in my patent Number 1,449,516 granted March 27, 1923, upon a combined catch and slide anchorage.

Formed integrally with the head and extending at an obtuse angle, or diagonally, therefrom is a shank (4) which is cut-away as at (5)—(5) adjacent the head, to form opposed reduced and flattened surfaces. An opening (6) is formed through the shank at the end of the reduced portion nearest to the free end of the shank, and trained through this opening is a substantially U-shaped, inherently resilient member forming tangs (7). The tangs are compressible to lie flat upon the flat surface of the shank, but the member as a whole is swingable in a semi-circle to engage into the substance of a base (not shown) into which the shank is projected. It being understood that the shank as a whole is to be projected into a wooden or other base to mount the anchorage thereon.

The shank (4) is further provided with a pair of opposed grooves (8)—(8) between the reduced portion and the free end thereof, and it will be noted that the grooves are arranged in the sides of the shank at right-angles to the cut-away portions (5)—(5). Drilled through the shank at the ends of the grooves nearest the free end of the shank is an opening (9) through which a second U-shaped, inherently resilient member forming tangs (10) is trained, and while this member

is rotatable within certain limits, it is restricted by engagement with the walls of the grooves.

In operation, a suitable opening is formed 5 in the material of the base (not shown) upon which the anchorage is to be placed, whereupon the shank of the anchorage is forced therein, the tangs (7) and (10) being compressible against the shank by the material 10 of the base. When the anchorage is subjected to any withdrawing action the tangs bite into the material of the base and positively lock the anchorage. Furthermore, if the material of the base is wood, and through 15 the deteriorating effect of age, or weathering it becomes weakened, the tangs will bite into the material and prevent accidental dislodgment of the anchorage.

It is here pointed out that the stress and 20 strain upon the anchorage by the weight of a person in harness attached thereto will tend to more securely lock the anchorage upon the base in direct proportion to the amount of weight, or the load, placed upon 25 it.

While in the foregoing, there has been described and illustrated such combination and arrangement of elements as constitute the preferred embodiments of my anchorage, 30 it is nevertheless desired to emphasize the fact that interpretation of the invention should only be conclusive when made in the light of the subjoined claims.

Having described my invention and its

objects with such attention to detail as will 35 thoroughly acquaint one skilled in the art with its construction and advantages, I claim—

1. An anchorage for window cleaners' harness comprising a head and a shank, a plurality of swingable members carried by the shank, and means formed on the shank for variably limiting the relative swingability of said members for the purpose set forth. 40

2. An anchorage for window cleaners' harness comprising a head and a shank, a plurality of swingable members carried by the shank, and each arranged to swing in an arc medially intercepted by a line defining 45 the longitudinal axis of the shank, and means formed on the shank for variably limiting the relative swingability of said members for the purpose defined.

3. An anchorage for window cleaners' harness comprising a head and a shank, said shank formed with grooves adjacent its free end, and flattened portions between the grooves and its head, the web of the flattened portions being longitudinally aligned with the grooves, and a plurality of swingable anchoring means one of which is seatable in the grooves and the other upon the flattened portions for the purpose defined. 55

In testimony whereof, I affix my signature 60 hereto.

BENJAMIN KUGLER.
